PROTECTIVE ATOMIZER CONTAINER OR
SIMILAR ARTICLE

Virginia M. Cook, 3161 Torrey Road, Flint, Mich.

Filed Feb. 3, 1964, Ser. No. 78,484

Term of patent 14 years

(Cl. D83—1)

FIG. 1

FIG. 2

FIG. 3

FIG. 4

FIG. 5

FIGURE 1 is a rear perspective view of a protective atomizer container or similar article showing my new design.

FIGURE 2 is a front perspective view thereof.

FIGURE 3 is a rear elevation thereof.

FIGURE 4 is a side elevation thereof.

FIGURE 5 is a front elevation thereof.

The undisclosed bottom portion of the medicament chamber is substantially flat and plain.

I claim:

The ornamental design for a protective atomizer container or similar article, substantially as shown and described.
